UNITED STATES PATENT OFFICE.

NEAL E. WOOD, OF CHANUTE, KANSAS.

SUGAR-DISPENSING DEVICE.

1,050,192.

Specification of Letters Patent. Patented Jan. 14, 1913.

Application filed May 11, 1912. Serial No. 696,786.

To all whom it may concern:

Be it known that I, NEAL E. Wood, a citizen of the United States, residing at Chanute, in the county of Neosho and State of 5 Kansas, have invented a new and useful Sugar-Dispensing Device, of which the following is a specification.

The device herein disclosed is a sanitary dispensing structure designed for table use 10 and adapted to be employed as an adjunct to a sugar bowl or like container.

The invention aims to guard against the spilling or wasting of the sugar in removing 15 it by spoonful from the sugar-bowl or vessel for table use.

A still further object is to carry out the aforesaid end in a simple, inexpensive and effective manner.

The invention consists of certain instrumentalities and features substantially as 20 hereinafter fully disclosed and defined by the appended claims.

In the accompanying drawing, illustrating 25 the preferred embodiment of my invention wherein it will be understood that such changes and modifications may be made as relate to the detailed construction and arrangement of the parts without departing from the spirit of the invention, Figure 1 is 30 a side elevation showing the invention as applied to a sugar bowl or vessel, for table use. Fig. 2 is a side elevation of the device removed from the sugar vessel. Fig. 3 is a sectional elevation of the device.

In putting my invention into practice, I 35 form a hollow or tubular stem member 1, having a spoon bowl or chamber 2 preferably of approximately conical outline, with which the stem or tubular member 1 has screw- 40 threaded connection, and a sleeve 3 and an annular jam nut 4, the sleeve and the nut being applied externally to an extended screw-threaded surface 5 upon the tubular or stem member 1, this surface extending 45 from the outer or upper end thereof inwardly.

As disclosed by Fig. 1, the tubular stem member 1 is inserted at its upper or outer end through a central orifice 6 provided in 50 the closure 7 of a sugar bowl 8.

The inserted end of the tubular stem member 1 has applied thereto, upon the under- 55 side of the sugar bowl closure 7, the jam nut 4, the sleeve 3 then being applied from the

upper side of said closure to said outer end 55 of the stem-member and screwed down tightly, its inner or lower end having a shoulder or flange 9 engaging the outer or upper surface of the sugar-bowl closure 7, thus providing for clamping the stem to the 60 bowl closure. The outer end of the sleeve 3 which also serves as a pouring nozzle or spout is closed by a plug or closure 10, for the retention of the sugar in the stem 1 when the bowl 8 is being supplied with sugar, and 65 is in inverted position, the plug or closure being removed, of course, in pouring the sugar.

It will be noted that when it may be desired to remove a spoonful or less of the 70 sugar from the bowl 8, it is only required to invert the latter, whereupon the sugar will enter the bowl 2 and the stem 1 and by then displacing the plug or closure 10 of the stem, the sugar will flow out. Also it will be 75 further observed that, by suitably adjusting the stem 1 toward or away from the bottom of the vessel the stem may be wholly or partially filled, thereby graduating the quantity of sugar removed. 80

It is to be observed that the device is perfectly sanitary and that the contents cannot become casually saturated; further, contents are well ventilated and are kept free from dirt and microbes. 85

What is claimed is:—

1. A device of the type described, including a tubular member or stem having a bowl or chamber applied to one end thereof with its containing portion in continuation of 90 the bore of said stem, said stem having externally applied thereto, at its opposite end, a sleeve one end of which is adapted to serve as a pouring spout, and having inserted therein a closure, and a jam-nut also applied 95 to said stem, said spouted sleeve having a flange at its inner end, adapted to coöperate with said jam-nut in applying the device for use.

2. A device of the type described, including a tubular member or stem having a bowl or chamber applied to one end thereof with its containing portion in continuation of the bore of said stem, said stem having externally applied thereto, at its opposite end, a 100 sleeve one end of which is adapted to serve as a pouring spout, and having inserted therein a closure, and a jam-nut also applied 105

to said stem, said spouted sleeve having a flange at its inner end, adapted to coöperate with said jam-nut in applying the device for use, said stem having an extended external 5 screw-threaded surface for said spouted sleeve and said jam-nut.

In testimony that I claim the foregoing as

my own, I have hereto affixed my signature in the presence of two witnesses.

NEAL E. WOOD.
